UNITED STATES PATENT OFFICE.

DAVID W. HYMAN AND CHARLES D. ORCUTT, OF DAYTON, OHIO, ASSIGNORS
TO THE ORIENT MFG. CO., OF DAYTON, OHIO, A CORPORATION OF OHIO.

UPHOLSTERING-MACHINE.

SPECIFICATION forming part of Letters Patent No. 721,804, dated March 3, 1903.

Application filed July 7, 1902. Serial No. 114,547. (No model.)

To all whom it may concern:

Be it known that we, DAVID W. HYMAN and CHARLES D. ORCUTT, citizens of the United States, residing at Dayton, in the county of 5 Montgomery and State of Ohio, have invented certain new and useful Improvements in Upholstering-Machines; and we do declare the following to be a full, clear, and exact description of the invention, such as will enable 10 others skilled in the art to which it appertains to make and use the same, reference being had to the accompanying drawings, and to the letters of reference marked thereon, which form a part of this specification.

15 This invention relates to improvements in machines for upholstering stools and possesses the new and useful features hereinafter described and claimed.

20 Preceding a detail description of the invention, reference is made to the accompanying drawings, of which—

Figure 1 is a front or rear elevation of our improved upholstering-machine, showing the same in the act of compressing the cushion material—such, for example, as excelsior. 25 Fig. 2 is a similar view showing the compression mechanism reversed after the act of compressing the cushion material or excelsior. Fig. 3 is a top plan view of the machine. Fig. 30 4 is an end elevation. Fig. 5 is a detail view. Fig. 6 is a detail view of the screw and adjunctive devices.

Throughout the specification similar reference-letters indicate corresponding parts.

35 A and B designate two parts of a rotatable frame, which have a hinge connection at C. Projecting from bosses D D on opposite sides of the lower frame A are spindles, which are journaled in boxes E, said boxes being supported on standards F F. The standards F F terminate in feet F' F'. The boxes E E are supported on one side of the standards F F as a matter of convenience in operating the machine. The spindle on one end of the 40 frame has secured to it a crank-handle G, by means of which the frame is turned to the reversed positions, as shown in Figs. 1 and 2.

As before stated, the upper member of the frame B is hinged at C and is in an operative 45 position when occupying the horizontal posi-

tions shown in Figs. 1 and 2. From this position it is elevated, as shown in dotted lines in Fig. 1. The said bar or member B is held in its horizontal or operative position by a dog H, which turns upon a pivot H', secured to the lower member A. The head of the dog is practically square, as in Figs. 3 and 5, and that end of the member B has a similar opening H'', so that when the dog is turned to the position shown in dotted lines in Fig. 5 the 55 said bar or member B may be elevated upon its hinge, as shown in the dotted lines in Fig. 1.

I designates a boss approximately in the center of the bar or member B and which has a screw-threaded opening which receives 60 a screw J, operated by a hand-wheel J'. The lower end of this screw has fixed to it a disk J''. Loosely attached to the extreme lower end of the screw J is a compression-plate K, between which and the rigid disk J'' there is 65 a series of ball-bearings a, said ball-bearings being inclosed in suitable ball-races in the disk J'' and the plate K.

L designates a concave or cup which is mounted on a pivot-pin L, which passes 70 through an opening in a boss L'', said boss being on the middle portion of the lower frame member A.

M designates a washer fixed to the lower end of the pivot-pin L' and serving to prevent 75 said pin from rising out of the opening in the boss L''.

The upper side of the frame A is provided with a disk N, in which is a suitable ball-race, and the lower side of the cup or concave L is 80 provided with a similar disk N', also provided with a suitable ball-race. Between these two disks there is placed a suitable number of ball-bearings O.

P designates a piece of carpet or other suitable fabric which forms the upper surface or covering of the stool when finished. This piece of carpet is laid over the top of the cup or concave L. P' designates a suitable quantity of filling or excelsior which is placed upon 90 said carpet, said excelsior being placed on the inner side of the carpet. P'' is a wooden slab or disk which forms the base of the stool when finished. This slab is placed above the excelsior or filling P' and below the compres- 95

sion-plate K. After the material for the construction of a stool is so placed the screw J is run down with suitable force to compress the fabric P and the excelsior P' into the cup 5 L until the wooden slab P'' is driven down to the limit which is prescribed by the rim of the cup L. The machine is then reversed to the position shown in Fig. 2 by turning the crank G. This brings the stool or body of 10 said stool in a convenient position for tacking the carpet or fabric P around its edge to the wooden slab P'', after which the surplus edge of said carpet is cut away, as shown in Fig. 2, and the body of the stool is removed 15 by running down the screw from the position shown in Fig. 2. The body of the stool is removed by elevating the upper member B of the frame. The down travel of the screw J is gaged or limited by a sleeve Q', which has 20 a flange on its lower end provided with ratchets c, that engage with a detent d, pivoted to the upper side of the bar B. These ratchets lock the screw against any backward movement after it has been driven down to the limit 25 of its movement in the operation of compressing the filling P'. The limit of such movement of the screw is determined by the position of the sleeve Q'. The said sleeve is moved up or down by a sleeve Q, which incloses the upper 30 end of the screw J below the hand-wheel J', the engagement between said sleeve being of a screw-threaded nature. A binding-screw b penetrates the upper sleeve Q and secures it fast to the screw-shaft after the lower 35 sleeve Q' has been moved to the proper position relatively to the bar B. It will be understood that the lower sleeve Q' is elevated or lowered by turning the upper sleeve Q. The screw-shaft J has a keyway, (shown in 40 dotted lines in Fig. 6,) into which a key projects from the lower end of the sleeve Q'. By this means the said sleeve may be moved up or down on said screw, while at the same time the said sleeve, together with the upper sleeve 45 Q, is rotated with the screw-shaft.

S is a spring-controlled latch, which is pivoted to an upright bar S' and serves to hold

the bar or member B in its elevated position, as shown in dotted lines in Fig. 1.

T is a spring-bar, one end of which is secured to one of the standards F. This bar has a loop T', into which the operating-lever G springs when the frame is in the position shown in Figs. 1 and 4.

Having described our invention, we claim— 55

1. In a machine for upholstering stools, a frame mounted for rotation comprising a lower curved member A and an upper straight member B, said members having a hinge connection, a cup or concave supported on the lower 60 member A and adapted to receive the fabric and filling under compression, a screw penetrating the upper member B, a disk attached to the lower end of said screw and adapted to compress the fabric and filling into said 65 cup or concave, and means for gaging the movement of said screw, substantially as set forth.

2. A machine for upholstering foot-stools, comprising a frame consisting of upper and 70 lower members A and B, which have a hinge connection, standards to which said lower member is pivoted and whereby the position of said frame may be reversed, a cup or concave mounted in the lower member of said 75 frame on antifriction-bearings, said cup or concave adapted to support the fabric, the filling, and the wooden slab from which the body of a stool is constructed, an operating-screw penetrating the upper member of the 80 frame, a disk attached to the lower end of said screw and adapted to make contact with the upper side of the wooden slab, and whereby the fabric and filling is compressed within the cup or concave upon the operation of lowering the screw, and means for operating said screw as set forth.

In testimony whereof we affix our signatures in presence of two witnesses.

DAVID W. HYMAN.
CHARLES D. ORCUTT.
